UNITED STATES PATENT OFFICE.

THOMAS I. DUFFY, OF OAK PARK, ILLINOIS.

VEHICLE-LAMP MOUNTING.

1,283,480.

Specification of Letters Patent.

Patented Nov. 5, 1918.

Original application filed January 15, 1917, Serial No. 142,402. Divided and this application filed September 10, 1917. Serial No. 190,426.

To all whom it may concern:

Be it known that I, THOMAS I. DUFFY, a citizen of the United States, and a resident of Oak Park, in the county of Cook and the State of Illinois, have invented certain new and useful Improvements in Vehicle-Lamp Mountings, of which the following is a specification, reference being had to the accompanying drawings, forming a part thereof.

This application is a division of my application No. 142,402, filed January 15, 1917, and now pending.

The purpose of this invention is to provide improved supports or mountings for vehicle lamps. It consists in the elements and features of construction shown and described, as indicated in the claims.

In the drawings:—

20 Figure 1 is a top plan view of a lamp equipped with mounting devices embodying this invention.

Fig. 2 is a rear view of the same.

25 Fig. 3 is a section at the line, 3—3, on Fig. 1, through the mountings only, that is, not cutting through the lamp which is shown in elevation.

Fig. 4 is a detail section at the line, 4—4, on Fig. 3.

30 Fig. 5 is a perspective view of one of the interchangeable bracket jaws.

In the drawings A represents a vehicle headlight lamp, the detail construction of which is the subject matter of my said application No. 142,402, and which is not illustrated or described in detail in this application. 2^b is a bail which embraces the upper portion of the casing of the lamp, A, and the free ends of which are apertured to receive pivot pins or studs, 2, by which the bail is pivoted to the lamp casing, the lamp thus hanging pendant in the bail. The casing, A¹, is provided opposite said free ends of the bail with hollow lugs, 4, which may be stamped outwardly upon the metal of the casing member. The inner ends of said studs are annularly grooved at 2^a to receive the slotted locking washers, 5, and between said washers and the inner faces of the end

50 walls of the hollow lugs, 4, are interposed resilient plates 6. Said plates are preferably of triangular shape with the corners turned out to constitute bearing points, and

are also preferably centrally depressed to receive the locking washers, 5. Interposed between the outer end faces of the said hollow lug, 4, and the apertured ends of the bail, 2^b, are friction washers, 7.

The said resilient plates, 6, coöperate with said friction washers, 7, to produce yielding friction joints between the ends of the bail and the lamp casing, of such nature that the lamp will be frictionally held in any position of adjustment on its pivot stud, and against accidental displacement by reason of vibration; but such adjustment may be varied by the application of moderate force applied to the lamp. The said hollow pivot lugs, 4, are sufficiently deep to receive the pin, 2, and the plates, 6, so that the inner cylindrical surface of the ring-like casing member, A¹, is free from projections, the presence of which would prevent the lens and its glazing ring passing freely into said casing member.

The lamp may be attached to a fixed support, 10, as one of the side stanchions of a wind shield when used on an automobile, by universal pivot means made as follows:

11 designates a bracket which is adapted to be detachably clamped at one end to said fixed support, and the other end of which is pivotally connected to the central portion of said bail, 2^b. The pivotal connection between said bracket and bail comprises, as shown herein, a stud, 13, which extends through the bracket and into a hollow lug, 14, formed in the central portion of the bail. The inner end of the pivot stud within the hollow lug, is slotted to receive a washer 15, and between said washer and the inner face of said hollow lug, there is interposed a spring plate, 16. Interposed between the bracket and stud head is a friction washer, 17. The construction described provides a yielding friction joint between the bracket and bail which permits adjustment of the stud, 13, by the exertion of a moderate amount of power against the lamp, while holding the lamp against accidental displacement under the ordinary vibrations of a motor car.

The bracket, 11, is so constructed as to fit a wide range of sizes and shapes of fixed supports. It comprises two like-shaped 105 sheet-metal arms, 18, which longitudinally

overlap each other at the outer end of the bracket and are apertured for the passage of the pivot stud, 13. The said arms, 18, at the inner end of the bracket swing toward 5 and from each other about the axis of the pivot stud, 13, in scissors fashion, and are adapted to grasp at their free ends the support to which the lamp is attached. The jaws of the bracket arms may be made integrally with said arms, preferably, however, as herein shown, the jaws, 20, are made separate from the arms and are detachably fitted thereto, so that jaws of different sizes may be interchangeably applied to said 10 arms. Said jaws may each consist of a single piece of sheet metal which is folded centrally to constitute two like leaves, and said sheet is cut away at its folded edge to produce spaced lugs, 21, which enter openings formed in deep vertical flanges, 23, at the sides of the brackets. Said flanges, 23, are curved at their outer edges to conform to the curvature of the bail. A clamping bolt, 24, which extends through registering apertures in said flanges, 23, and is provided with a screw threaded nut, 25, constitutes means to clamp the jaws on a fixed support.

The provision of the separately formed detachable jaws, 20, makes it practicable to 30 furnish a plurality of different sized jaws at an inconsequential expense with each bracket, so as to thereby enable the jaws of the bracket to be accurately fitted to supports of widely different sizes and shapes. 35 The jaws may be made of relatively light metal, whereby they may be specially formed to a limited extent when the bracket is fitted in place on the support, and thus insure a neat and reliable fit of the jaws to 40 the support. No fastening means are required to fit the jaws to the bracket arms, inasmuch as the clamping pressure of the bolt, 24, serves, when the parts are installed, to fixedly hold the jaws in place.

45 The advantage of pivoting the clamping arms, 18, of the bracket to the pivot stud, 13, by which the bracket is connected to the bail, is, that thereby the free ends of said arms and the jaws carried thereby have a very 50 wide range of adjustment toward and from each other to adapt the bracket to fixed supports of widely different dimensions.

It is to be understood that the invention 55 may assume other specific embodiments within the broader phases thereof, as set out in the appended claims, and that the invention is not limited to the embodiment shown except as to the claims wherein the same is specifically pointed out.

60 I claim:—

1. A universally adjustable lamp comprising a casing, a bail pivoted at its lower ends to said casing, a horizontal bracket comprising two sheet metal arms having 65 overlapping outer ends and vertically

flanged inner ends, a stud for pivotally connecting the outer ends of said arms together and to the bail and a clamping bolt extending through the flanged ends of said arms.

2. A universally adjustable lamp comprising 70 a casing, a bail pivoted at its lower ends to said casing, a horizontal bracket comprising two sheet metal arms having flat, horizontally disposed overlapping outer ends and vertically flanged inner ends with 75 the lower edges of said flanges curved to correspond to the curvature of the bail, and a pivot bolt extending through the overlapping arms of said bracket and the central portion of said bail.

3. In a lamp mounting, a bracket comprising 80 two arms pivoted for swinging about the pivot to separate and close at their free ends, in combination with interchangeable jaws detachably fitted to said free ends.

4. In a lamp mounting, a bracket comprising pivoted arms and clamping jaws, each jaw consisting of a sheet metal member folded upon itself to form two leaves, with means to detachably fit the jaws to said arms. 90

5. In a lamp mounting, a bracket comprising pivoted members provided at their free ends with apertured flanges, jaws provided with lugs to removably enter the apertures of the flanges and a clamping bolt extending 95 through said flanges.

6. In a lamp mounting, a bracket comprising pivoted members provided at their free ends with spaced openings, and jaws, each comprising a sheet metal member folded between its ends to form two leaves, said sheet being notched at its folded edge to provide spaced lugs to enter said openings. 100

7. A lamp comprising a sheet metal casing having oppositely disposed integral hollow pivot lugs, a bail, pivots connecting the lower ends of said bail to said lugs, and resilient members applied to said pivots to afford resilient friction joints between said bail and casing, said resilient members being contained within said hollow lugs. 105

8. A lamp comprising a casing, a bail pivoted at its lower ends to the opposite sides of said casing and provided at its central portion with a hollow boss, a bracket frictionally engaging said boss, a pivot to connect the bracket to the boss, and a resilient member applied to said latter pivot within said boss to force together the friction surfaces between the bracket and bail. 115

9. The combination with a member formed with a hollow pivot lug having a partially closed end, of a pivoted member, a pivot stud extending through the latter member and said end of said lug, a spring plate applied over the inner end of said stud and bearing against said end of the lug and means to hold said plate on the stud. 125

10. The combination with a member formed with a hollow pivot lug having a 130

partly closed end, of a pivoted member, a pivot stud extending through the latter member and said end of said lug, a spring plate applied over the inner end of said stud and bearing against said end of the lug, the inner end of the stud being grooved and a plate retaining washer fitting the grooved end of said stud.

11. The combination with a member formed with a hollow pivot lug having a partly closed end, of a pivoted member, a pivot stud extending through the latter member and said end of said lug, a spring plate applied over the inner end of said stud and bearing against said end of the lug, the inner end of the stud being grooved and a plate retaining washer fitting the grooved

end of said stud, said spring plate being centrally depressed to receive said washer.

12. The combination with a member 20 formed with a hollow pivot lug having a partly closed end, of a pivoted member, a pivot stud extending through the latter member and said end of said lug, a spring 25 plate applied over the inner end of said stud and bearing against said end of the lug, and a friction washer between the outer face of said end of said lug and said pivoted member.

In testimony whereof, I have hereunto set 30 my hand at Chicago, Illinois, this 6th day of September, 1917.

THOMAS I. DUFFY.
